CLAIM

The ornamental design for a bathroom fixture, as shown and described.

DESCRIPTION

FIG. 1 is a perspective view of my design for a bathroom fixture;

FIG. 2 is a top plan view thereof;

FIG. 3 is a front elevation view thereof;

FIG. 4 is a back elevation view thereof;

FIG. 5 is a bottom plan view thereof;

FIG. 6 is a left side elevation view thereof; and,

FIG. 7 is a right side elevation view thereof.

The broken lines shown in the figures represent portions of the bathroom fixture that form no part of the claimed design.
